DOLL CRAWLING MECHANISM

Robert Gardel, 11 Riverside Drive, New York 23, N.Y., and Arthur Rogovin, 32-25 Mott Ave., Far Rockaway, N.Y.

Filed Apr. 21, 1958, Ser. No. 729,581

4 Claims. (Cl. 46—149)

This invention relates to a doll crawling mechanism, and particularly to such a mechanism in which the movements of a doll's limbs are so coordinated that the movement of any one or two limbs causes predetermined corresponding movement of the other three or two limbs.

An object of the invention is to provide arm moving mechanism coupled to leg moving (walking) mechanism so that reciprocating movements of the legs, as in walking or crawling, will cause simultaneous movements of the arms, either swinging or crawling.

Another object is to provide such mechanism with manual operating means for either walking or crawling.

A further object of the invention is to provide such mechanism of a strong and simple character, having a frame capable of constituting the entire "skeleton" of a doll, whether the body is formed of rigid material or of relatively soft flexible flesh-like material such as vinyl plastics.

Another object is to provide certain improvements in the form, construction and arrangement of the several parts whereby the abovenamed and other objects may effectively be attained.

Practical embodiments of the invention are shown in the accompanying drawings, wherein—

Fig. 1 represents a side view of a doll which may contain mechanism of any of the forms shown, in standing or walking position;

Fig. 2 represents a side elevation, with the doll body and limbs outlined by broken lines, of a doll containing a form of mechanism designed to make the limbs move in lateral pairs ("pacing") instead of in diagonal pairs ("trotting") as in copending continuation-in-part application Serial No. 814,814 filed May 21, 1959;

Fig. 3 represents a front view of the mechanism shown in Fig. 2;

Fig. 4 represents a detail longitudinal section on the line IV—IV of Fig. 3;

Fig. 5 represents a detail longitudinal section on the line V—V of Fig. 3;

Fig. 6 represents a side elevation, with parts broken away and parts in section, viewed from the direction of the line VI—VI in Fig. 7, showing a further modified form of mechanism, manually operable by means of a reciprocating bar;

Fig. 7 represents a front view, with the doll body front wall removed, of the mechanism shown in Fig. 6, the operating bar being in its pressed-in position;

Fig. 8 represents a transverse section on the line VIII—VIII of Fig. 7, the operating bar being shown in full lines in its released position and in broken lines in its pressed-in position, and

Fig. 9 represents a detail perspective view of the operating bar itself.

Referring to the drawings, it will be understood that the mechanism shown herein is not automatic, and that a doll is made to execute the crawling or creeping motion (after the limbs have been adjusted to suitable positions)

2

by having its body held and advanced with a slight rocking movement to cause first one knee (or hand) and then the other knee (or hand) to engage most strongly with the supporting surface. With the form shown in Figs. 1 to 5 (pacing), the knee and hand on one side can both engage the surface while the knee and hand on the other side are advancing, i.e., nothing more is needed than rocking and advancing. And with the modification of Figs. 6 to 9 the limbs are caused to move by the lateral squeezing of the body rather than by engagement with the supporting surface.

While the crawling mechanism may include, as part of the combination, various specific types of walking mechanism, that shown herein is of the type covered by Gardel and Rogovin Patent No. 2,736,135, issued February 28, 1956, with reference particularly to Figs. 8 and 9 thereof. For convenience and uniformity in description, the orientation of the mechanism will be considered to correspond to the erect (walking) position of the doll unless otherwise noted.

The mechanism comprises a vertical plate 1 engaged at its top with a horizontal plate 2; said plates having (particularly in vinyl body dolls) outlines corresponding substantially to the desired internal shape and size of the body from the waist down. The plate 2 is fixed to the body wall at suitable points as indicated by the provision of eyelets 3, 3, to receive rivets (not shown) and the upper inner part of the plate 1 may be cut out and bent to form the reinforcing brackets 1', 1' which hold the plates 1 and 2 quite rigidly in perpendicular planes.

In addition to the plates 1, 2, which support the walking mechanism per se, there is provided also an upwardly projecting frame member 4 of approximately T-shape having forwardly bent triangular braces 4', 4' at its base secured to the plate 2, having its outer ends bent forward at right angles and perforated to form arm support bearings 29, 29.

Leg mounting members 9, 9 (similar to the members 28 in the patent cited above) are pivotally mounted on the lower part of the plate 1 by a rivet 10 or the like, for rocking motion about a horizontal axis. Adjacent the flat vertical lower ends of the members 9, 9 which rest against the plate 1, each said member has an outwardly slanted part 9', 9', above which the members terminate in narrow vertically extending pins 11, 11, projecting through slots in the plate 2. Each leg is secured to its member 9 by means of a mounting "button" 13 through which passes a post 14 projecting perpendicularly from the slanting part 9' and having a spring 15 bearing against the head of the post and the button, to urge the latter into engagement with the part 9'. The button is preferably seated on a base 16 having a small projection (not shown) adapted to engage one or more grooves or depressions in the part 9' so as to hold the leg releasably at least in the standing position while permitting it to be turned to the sitting or crawling position. A knee joint which may be, for instance, of the type shown in Gardel and Rogovin Patent No. 2,791,063, issued May 7, 1957, is also provided so that the legs can be moved to the crawling position, and can also be straightened out for standing and walking.

The walking mechanism is completed by the provision of a rocker 17, fixed on the driving rod 25 and having radial slots designed to receive the pins 11, 11. The rod 25 is journaled at one end in the plate 2 and at the other end in the turned-up lug 35 in which it extends to a point above the arm axis where it bears a rocker 26 adapted to engage and actuate the upwardly projecting ends of the cranks 27, 27, the outer ends of which are rockably mounted on a horizontal axle 28 journaled in

the upturned lugs 29, 29. The arm mounting buttons 21, 21 are similar to those for the legs in that they each contain a spring bearing outwardly against a washer 22 and urging the base 30 of the button into engagement with the corresponding crank 27, and each said base 30 having a projection adapted to engage a slot 31 in the crank 27. A comparable projection on the base of the leg mounting button is shown at 32 in Fig. 2. In the operation of this mechanism the limbs move in lateral pairs, both right limbs going in the same direction at the same time and both left limbs doing likewise. Thus in crawling, the left hand and knee can both be pressed firmly against the supporting surface while the body is moved forward and the right hand and knee swing to their foremost position, then the doll is rocked to bring the right limbs down while the left ones move forward, and so on.

The rod 25 is offset as shown at 25' in order to pass the axle 28 while keeping the axis of rotation of the rocker 26 in the plane of said axle. The upper end 33 of the frame is shown here as being made from a separate piece of metal firmly fixed on the main frame 34 as shown in Figs. 3 and 4, for instance, this arrangement being convenient because some doll makers wish a neck ring structure of the type shown while other might wish to have other forms of neck and head supports, while retaining all the rest of the crawling mechanism. In the present form it is convenient to journal the upper end of the rod 25 in a lug 35 stamped and turned up from the part 33, the opening thus formed being useful in connecting the parts 33 and 34.

Some children, particularly small ones, are apt to experience difficulty in operating crawling dolls by the normal "rocking" methods applicable to the structure of Figs. 2 to 5. This difficulty is overcome by the addition of features shown in Figs. 6 to 9 in which the crawling (and walking) mechanism is basically the same as that of Figs. 2 to 5. The driving rod 36, however, is provided with an offset crank portion 36', about at the middle of the doll's body. An operating bar 37 is slidably supported in alined openings through the parts 38, 39 of a bracket fixed to the main frame 40, one end of said bar being in engagement with the crank portion 36' (which passes through the opening 37', for instance) and the other end being provided with a pusher 41 in the form of a button (or even a bent-over end of the bar itself) to constitute a smooth "land" of substantial area adapted to bear against the inner surface of the doll body (e.g., between the waist and armpit) when the bar 37 is at its limit of travel in that direction. A compression spring 42, preferably designed to exert a substantially constant force throughout its range of operation, bears against a bracket 43 fixed to the main frame adjacent the inner surface of the doll body in an area diametrically opposite the area contacted by the pusher 41 and engages the crank end of the bar 37, urging said bar in the direction to put the pusher 41 in contact with the body. The limits of travel of the bar 37 correspond to the limits of forward and backward movement of the doll's limbs during crawling or walking.

In operation, the body of the doll need only be grasped and squeezed laterally—and intermittently—in order to cause the driving rod to rotate back and forth and thus make the limbs execute their crawling or walking motions. The driving rod is rotated in one direction by positive manual pressure pushing the bar 37 against the force of the spring 42, and is rotated the same distance in the opposite direction when the manual pressure is released, permitting the spring to expand and return the parts to their original position.

The spring should be strong enough to operate promptly and reliably while still being soft enough to be compressi-

ble by the grip of a small child. Since one end of the bar 37 engages the crank portion 36' it may be possible to omit the part 38 (or 39) in small dolls; otherwise the parts 38, 39 serve not only as guides and supports for the bar 37 but also limit its endwise motion. It will be evident that other types of springs could be used and that a spring or springs might be connected to the moving parts at one or more other points in the system; since the linkage is completely "reversible" the resilient force may be applied at any convenient point with substantially the same effect. Likewise the guiding openings in the parts 38, 39, or either of them, can be replaced by one or more guide links between the bar 37 and the frame, or the bar 37 might have its outer end fixed to the body wall so as to eliminate the need for any additional guiding means.

It will be understood that other changes can be made in the form, construction and arrangement of the several parts without departing from the spirit and scope of the invention.

What we claim is:

1. A doll crawling mechanism comprising, a rigid frame having a horizontal part shaped to fit within a doll body at approximately the waist line, a vertical part fixed to the horizontal part and extending downwardly therefrom and an upper part fixed to the horizontal part and extending upwardly at least to approximately shoulder height, leg mounting members attached to the lower vertical part for oscillation about a horizontal axis, pins connected to said members and projecting upward through slots in the horizontal frame part, arm mounting members attached to the upper frame part for oscillating movement about a fixed horizontal axis, cranks connected to said arm mounting members and projecting away from said axis, a driving rod having its ends journaled in said frame, a first rocker fixed on said driving rod adjacent its lower end and provided with apertures to receive the said pins and a second rocker fixed on said driving rod adjacent its upper end and provided with apertures to receive the said cranks, said first rocker being above the axis of rotation of the leg mounting members and said second rocker being above the axis of rotation of the arm mounting members.

2. A mechanism according to claim 1 in which the driving rod is provided with a crank portion, and which includes means operable by pressure on the doll body for moving said crank to oscillate the driving rod.

3. A mechanism according to claim 2 in which said last named means comprises an operating bar engaging the crank and having an end movable to a point adjacent the inner wall of the doll body, means for guiding said bar along a predetermined path, and means resiliently urging said bar in a direction to move said end to said point.

4. A mechanism according to claim 2 in which said last named means comprises an operating bar engaging the crank, means for guiding said bar for substantially rectilinear reciprocating movement in the direction of its length and means resiliently urging said bar in a direction to move one of its ends to a point adjacent the inner wall of the doll body.
